Primary Examiner — Susan Moon Lee

(57) **CLAIM**

The ornamental design for a pet nail clipper, as shown and described.

DESCRIPTION

FIG. 1 is a front perspective view of a pet nail clipper according to my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom view thereof; and

FIG. 9 is an in-use, expanded front perspective view thereof.

The broken lines in the drawings illustrate portions of the pet nail clipper which form no part of the claimed design.
